UNITED STATES PATENT OFFICE

GEORGE L. MARCUM, OF WILLIAMSON, WEST VIRGINIA; ETHEL MARCUM, ADMINISTRATRIX OF SAID GEORGE L. MARCUM, DECEASED, ASSIGNOR OF SIXTY-FIVE PER CENT TO ETHEL MARCUM, INDIVIDUALLY AND AS LEGAL GUARDIAN FOR EDNA LEE MARCUM AND GEORGE LEE MARCUM, FIFTEEN PER CENT TO W. C. BROWN, AND TWENTY PER CENT TO C. O. BURRESS, ALL OF WILLIAMSON, WEST VIRGINIA

COMBINATION FRAMING TOOL

Application filed March 20, 1928. Serial No. 263,198.

My present invention has reference to a framing tool for carpenter's use, and my primary object is the provision of a tool for this purpose which will enable the carpenter to readily ascertain the lengths and cuts of common jack, hip and other regular or irregular rafters without resorting to the employment of a steel or framing square.

Another object is the provision of a framing tool that includes a handle and a blade which is pivotally associated with the handle through the medium of removable discs, which latter have inscribed thereon a protractor or degree scale as well as other marks of graduation designed to be brought into alignment with marks or graduations arranged in circular relation on the handle of the tool, the protractor or degree scale being disposed opposite a pointer mark on said handle, whereby the blade may be turned on the handle to arrange these parts at determined degrees or whereby the rise per inch and the different angle of cuts of jack or other rafters may be obtained, the blade being suitable scaled to correspond with the scales on the discs and handles.

To the attainment of the foregoing and other objects which will present themselves as the nature of the invention is better understood, the improvement also resides in certain other novel features of construction, combination and operative association of parts, one satisfactory embodiment of which is disclosed by the accompanying drawings.

35 In the drawings:

Figure 1 is a side elevation of the improvement.

Figure 2 is a similar view but looking toward the opposite side of the improvement.

40 Figure 3 is a sectional view approximately on the line 3—3 of Figure 5.

Figure 4 is a sectional view approximately on the line 4—4 of Figure 1.

45 Figure 5 is a sectional view on the line 5—5 of Figure 2.

Figure 6 is a plan view looking toward one end of the blade.

50 Referring now to the drawings in detail, the numeral 1 designates the handle of the improvement. The handle is preferably

widened on one end thereof, and this end of the said handle is rounded, but the same is provided with a lug extension 2. The rounded portion or head of the handle may be either integrally formed or may provide a separate element from the remainder of the handle. By reference to Figure 4 it will be seen that the inner edge of the handle is widened outwardly, as at 3. This is to permit of the said edge of the handle more firmly contacting with the edge of a piece of lumber against which it is arranged. The handle, from its said inner and widened edge 3 is slotted longitudinally to provide the same with a pocket 4, and the inner wall of the pocket entering the rounded end of the handle has its rear wall also rounded and terminates in a line with the lug 2. The rounded end of the handle is provided with a central opening 5.

The blade is broadly indicated by the numeral 6, the same having its edge at one of its corners formed with a rounded projection 7 that is designed to be received in the rounded portion of the pocket 4. The straight shoulder 8, provided at the end of the blade proper is designed to contact with the lug 2 to hold the blade at a right angle with respect to the handle 1 whereby the tool may be employed as a square.

70 The rounded portion 7 of the blade 6 is provided with a central opening 9 and with equidistantly spaced radially disposed openings 10 that are arranged outward of the said opening 9. The openings 10 are designed to receive therethrough pins 11 that extend from the inner reduced and annular face 12 of a disc 13. The pins 11 also enter pockets in a second disc 14 whose inner reduced and rounded face 15' is passed through the opening in the second side of the handle. There is passed through a central opening in the disc 13, the opening 9 in the blade 6 and threaded in a central opening in the disc 14 a screw or bolt member 15, the disc 13 being reamed around the opening of the said screw or bolt so that the head of the said screw or bolt is pocketed in the disc. By adjusting the element 15 the discs 13 and 14 may be brought into frictional contact with the op-

posite faces of the handle to compress the same against the part 7 of the blade 6, and thereby sustain the blade when swung at different angles on the handle. The reduced portions 12 and 15' of the respective discs are in the nature of hubs and contact with the rounded or what may be termed the hub portion of the blade.

By reference to the drawings it will be noted that the disc 14 is of a slightly less size than the disc 13 and that both the discs have their outer faces beveled from their edges.

The disc 14, from its said beveled edge is graduated, as at 16, and the said graduations in the showing of the drawings are numbered from 3 to 16, and these figures are for the purpose of obtaining the side cuts of jack rafters, the span in feet and the rise in inches of said rafters being inscribed by scales on the blade 6 as will hereinafter be described. For the purpose of illustration we will suppose that in framing a hip roof on say an 8 and 12 pitch to obtain the side cut of the jack rafters, it is merely necessary to swing the blade and the disc to bring the indicating mark 8 on the disc opposite the figure 8 on one of the circular graduations 17 on the handle and thus obtain the proper angle. It should be stated that the principle in using my improvement is the same as that employed in the use of a steel square or a framing square. In addition to the circular graduations on the handle that surround the disc 14 there are other annular series of graduations each suitably marked, and whereby the side cuts of jacks differently spaced may be readily ascertained by simply swinging the blade as above mentioned.

The side of the handle illustrated in Figure 1 of the drawings has its inner edge inscribed with spaced numerals to indicate plumb cuts and corresponding seat cuts, and the outer edge of the blade 6 on the face thereof disclosed by Figure 1 of the drawings is provided with a ruled scale 18 and inward of the ruled scale the blade has inscribed thereon numerals 19 to indicate the span in feet of the jack or other rafters. Below the numerals 19 the blade is divided by longitudinal and transverse lines into columns of figures to indicate the rise in inches of the rafter according to the rise per inch in the run of the rafter, and according to the width of the building. In the showing of Figure 1 the character 12 is arranged in the center and a little above the abbreviations for the common or for the hip rafters, and the character 12 indicates that the building is 12 ft. wide, the other numerals in a line with the numeral 12 indicating other widths of buildings.

On the opposite side of the blade disclosed by Figure 2 the portion thereof nearest the handle is provided with a lumber measurement scale 20 and with figures indicating the

span in feet of a building, columns in which are inscribed figures indicating the rise in inches of common and hip rafters, these scales being a continuation of the scales shown on the face of the blade in Figure 1. The disc 13 is shown on this face of the scale, and the same has inscribed thereon a degree or protractor scale 21 whose markings are arranged to align with an arrow or like indicator 22 on the top portion of the handle 1. Approximately diametrically opposite the protractor or degree scale the disc 13 has inscribed thereon a numbered scale 23 to indicate the side cut of hip rafters, the scale in the present instance being from 2 to 16. This scale 23 is designed to have its markings brought opposite a numbered scale 24 on the handle 1. The inner edge of the handle 1 upon this side thereof and opposite the scale 24 has inscribed thereon numerals 25 to indicate the plumb cut of hip brackets and below them another scale 26 to indicate the seat cut of hip rafters. In addition to this the face of the scale may have arranged or inscribed thereon discs, squares, etc., having angle lines marked thereon and indicia relative to the position at which the blade is to be turned on the handle to obtain desired mitre cuts.

With my improvement the lengths and cuts of rafters in the framing of a building may be easily obtained by a carpenter who is unacquainted with the use of a steel square and in a more expeditious manner. The improvement it will be noted provides a combined square, bevel and protractor, and the simplicity and advantages of the construction will, it is thought, be fully understood and appreciated without further detailed description. Of course, discs having different scales than those illustrated may be employed when different angle cuts are required, and as a matter-of-fact, I propose to commercialize the improvement in a number of such styles and likewise with a book of instructions as to the use of the tool, it being understood that the description as herein set forth, merely is intended to convey certain purposes and methods for accomplishing desired results by the employment of the improvement.

It will be apparent that when the blade is folded into the handle the tool can be easily carried in the pocket of the carpenter or conveniently stored in his tool box.

The outer or headed end of the handle may and preferably has arranged in a socket therein a spring influenced headed latching bolt 28. The inner end of the bolt is flared to a point, as indicated by the numeral 29 and the said end of the bolt is designed to be received in substantially V-shaped notches 30 in the periphery of the rounded portion 7 of the blade 6. The notches 30 are preferably so spaced that the blade will be held at a right angle with respect to the handle when the locking dog is received in one of the notches 30

and the said blade 6 will be held at an angle of 45 degrees with respect to the handle when the locking device is received in the second notch. Obviously the end 7 of the blade may be provided with additional notches. The locking bolt 28 passes through a central opening in a metal bushing 31 which is screwed in the socket 33 for the said bolt. This bushing 31 has a notch 34 therethrough and the locking bolt has a pin 35 that is received in the notch. The spring 36 contacts with the bushing and also with a disc enlargement or flange 37 on the locking bolt. It will be apparent that the flange 37 will prevent the locking bolt from being entirely withdrawn from the socket or opening therefor and it will be further apparent that by exerting an outward pull upon the headed end of the locking bolt to bring the pin out of the notch in the bushing and thereafter turning the locking bolt to bring the pin away from the notch, the active end 29 of the bolt will be brought out of engagement with the notches in the end 7 of the blade.

As disclosed by the drawings, the pivot bolt 15 has one of its ends engaged by a wing nut 39, the adjustment of which permits of ready swinging of the blade on the handle, and for likewise causing the bifurcated end of the handle to exert a frictional contact with the blade for holding the latter from free turning on the pivot bolt 15.

Having described the invention, I claim:

1. A framing tool comprising a slotted handle which is provided adjacent to one end with a round opening, a blade swingable into and out of the slot of the handle, discs having hub portions adapted to be received through the opening from the opposite sides of the handle to provide a pivot between the blade and handle, interengaging means for the discs passing through the blade, a binding element passing centrally through the discs and through the blade for compressing the sides of the handle against the blade, one of said discs bearing a degree scale, and the handle having an arrow-shaped pointer designed to register with degree marks on the discs when the blade is swung pivotally with respect to the handle.

2. A framing tool comprising a handle which is slotted longitudinally from one of its edges, and which slot has an inner rounded depression adjacent one of its ends, said handle having a round transverse opening therethrough which communicates with the depression, a blade having graduations and mathematical tables inscribed thereon and having one of its corners formed with a peripherally round extension to be received in the rounded depression in the handle, discs, hub portions on the discs adapted to be inserted from the opposite sides of the handle into the opening, pins extending from one of the discs to be passed through the round end

portion of the blade and said pins being received in the hub of the second disc, an adjustable binding element passing through the discs and through the blade, the end of the blade, adjacent the rounded portion thereof adapted to contact with a portion of the handle when the blade is swung to a right angle on the handle, said discs having their peripheral edges beveled and provided with graduations and the sides of the handle, adjacent the discs bearing an annular series of graduations, for the purpose set forth.

3. A framing tool comprising a handle which is slotted longitudinally from one of its edges, and which slot has its inner wall formed with a rounded depression adjacent one end of the handle, said handle having a round opening which communicates with the depression, and said handle having a lug projecting from said end, a blade having scales and tables inscribed thereon and having one of its corners formed with a peripherally rounded extension to be received in the rounded depression in the handle, discs having hub portions inserted in the opening from the opposite sides of the handle, pins extending from one of the discs designed to be passed through the rounded extension of the blade and to be received in the hub of the second disc, an adjustable binding element passing through the discs and through the said extension on the blade, the end of the blade adjacent the rounded extension thereof designed to contact with the lug of the handle for holding the blade at a right angle with respect to the handle and said blade being swingable into the slot of the handle, said discs having their peripheral edges beveled and provided with graduations, the sides of the handle, adjacent the discs being provided with annular series of graduations, and the slotted edges of the handle being widened outwardly and provided with graduations.

4. A framing tool comprising a slotted handle having a transverse opening which communicates with the slot, a blade which is swingable into and out of the slot of the handle, discs providing a pivot between the blade and the handle, said discs having hub portions to be inserted in the opening from the opposite sides of the handle, interengaging means connecting the discs and passing through the blade, a bolt passing centrally through the discs and the blade, and a binding element on said bolt for contacting with one of the discs.

5. A framing tool comprising a slotted handle having a round depression therein and having a round transverse opening that communicates with the said depression, and a blade which is swingable into and out of the slot of the handle, one corner of the blade being extended and having a round portion to be received in the depression of the handle and the said rounded portion being formed with spaced V-shaped notches, pivot discs

- having hub portions let in the opening from the respective sides of the handle for contacting with the opposite faces of the said rounded portion of the blade, interengaging means connecting the discs and the said portion of the blade, a binding element for the discs, and a spring influenced locking bolt received through the handle and engageable in any of the notches of the rounded portion of the blade.
6. A framing tool comprising a handle which is slotted and which is provided with a round depression in its said slotted portion and which has a round opening communicating with said depression, a blade which is swingable into and out of the slot of the handle, one corner of the blade being extended, peripherally rounded and formed with spaced V-shaped notches and which extension is received in the round depression in the handle, pivot discs having hub portions let in the opening from the opposite sides of the handle for contacting with the opposite faces of the said corner extension on the blade, interengaging means between the discs and the said extended portion of the blade, a binding element for the discs, a spring influenced locking dog received through the handle and having a pointed end to be engaged in any one of the mentioned notches, a notched bushing through which the dog passes, and a pin on the locking dog normally received in the notch of the bushing.

In testimony whereof I affix my signature.
GEORGE L. MARCUM.
